Attorney

UNITED STATES PATENT OFFICE.

CHARLES W. WATKINS, OF DORRANCETON, KINGSTON, PENNSYLVANIA.

CAR-REPLACER.

1,264,233.

Specification of Letters Patent. Patented Apr. 30, 1918.

Application filed March 2, 1918. Serial No. 219,982.

To all whom it may concern:

Be it known that I, CHARLES W. WATKINS, a citizen of the United States, residing at Dorranceton, Kingston, in the county of Luzerne and State of Pennsylvania, have invented certain new and useful Improvements in Car-Replacers, of which the following is a specification, reference being had to the accompanying drawings.

10 This invention relates to certain improvements in car replacers and it is an object of the invention to provide a novel and improved device of this general character whereby the wheels of a car may be returned 15 to the rails with a minimum of effort and labor.

It is also an object of the invention to provide a novel and improved device of this general character which may be employed 20 in connection with either the inside or the outside of a rail and wherein the device is provided with means for causing the flange of a wheel to pass over the head of a rail when the device is employed in conjunction 25 with the outer side of a rail.

Another object of the invention is to provide a device of this general character with novel and improved means whereby the same may be anchored to the rail with which it 30 acts and which is also provided with means to prevent the same from slipping especially when positioned upon an ice-coated surface.

A still further object of the invention is to provide a novel and improved car replacer 35 provided with a bearing surface arranged on a predetermined incline and upon which the tread of a wheel directly contacts.

The invention consists in the details of construction and in the combination and 40 arrangement of the several parts of my improved car replacer whereby certain important advantages are attained and the device rendered simpler, less expensive and otherwise more convenient and advantageous 45 for use, as will be hereinafter more fully set forth.

The novel features of my invention will hereinafter be definitely claimed.

In order that my invention may be the 50 better understood, I will now proceed to describe the same with reference to the accompanying drawings, wherein:

Figure 1 is a view in top plan of a car replacer constructed in accordance with an 55 embodiment of my invention and disclosed as coacting with the outer side of a rail, a

second hook being extended for the purpose of disclosure;

Fig. 2 is a longitudinal sectional view taken through my improved car replacer as 60 herein embodied, a coacting rail being indicated by dotted lines;

Fig. 3 is a sectional view taken substantially on the line 3—3 of Fig. 1; and

Fig. 4 is a sectional view taken substantially on the line 4—4 of Fig. 2 and showing my improved replacer coacting with the inner side of a rail.

My improved car replacer is preferably made of metal and includes an upwardly and longitudinally inclined body plate P having its marginal portions defined by the depending flanges 1. The contacting marginal portions of the flanges 1 are provided with the teeth 2 whereby the device is effectively prevented from creeping when the device is positioned upon an ice-coated or slippery supporting surface.

The plate P is provided with a pair of flange receiving grooves 3 converging toward the lower end of the plate and said flanges gradually decrease in depth and width toward the upper end of the plate P. The portion 4 of the plate intermediate the grooves 3 is flat and serves as a bearing surface to directly receive the tread of a wheel positioned outwardly of a rail. The portion 4 is provided with an extension 5 extending a predetermined distance beyond the upper end of the plate P and the outer end portion 90 of the extension 5 is in convergence. As is particularly illustrated in Fig. 1 it is to be noted that the extension 5 includes a long side 6 and a short side 7. When my improved replacer is employed in connection 95 with the outer side of a rail the long side 6 is positioned immediately adjacent the rail and when my improved device is employed in connection with the inner side of a rail, the short side 7 is positioned adjacent the 100 rail.

The extension 5 has its marginal portions defined by the depending flanges 8 which are provided at their lower margins with the substantially horizontally disposed flanges 9. 105 The flanges 9 however, are arranged on such an inclination as to overlie a base flange of a rail R as is believed to be clearly illustrated in Fig. 3. The flanges 9 as herein disclosed extend beyond opposite sides of the flanges 8 and the inner marginal portions of the flanges 9 are provided with the depend-

ing teeth 10 for the same purpose as the teeth 2 hereinbefore referred to. In order to impart additional strength to the upper portion of the plate P, I find it of advantage 5 to depend therefrom the transversely disposed flange or lid 11.

I also find it of advantage to provide the converging portions 9^a of the flanges 9 with the notches or recesses 12 which are adapted 10 to receive the bolt heads or nuts at a rail joint should my improved replacer be employed at such a location. By the use of the notches or recesses 12 it will be self-evident that such bolt heads or nuts will offer 15 no obstruction to the proper positioning of my replacer.

The groove 3 at the short side of the device has its outer longitudinal marginal portion defined by the surface 14. The upper 20 portion of said surface 14 is intersected by the vertically disposed groove or recess 15 in which is arranged the vertically disposed loop member 16. Loosely engaged with the intermediate portion of the loop 16 is the 25 hook member 17 which is adapted to engage over the head of a rail when my improved replacer is employed in connection with the inner side thereof and as is particularly illustrated in Fig. 4. The inner portion of 30 the hook member 17 is downwardly off-set as at 18 so that said hook member will offer no obstruction to the flange of a wheel properly mounted or engaged with the rail.

The upper end of the extension 5 is provided 35 with the up-standing shoulder 19 extending entirely across the outer end portion of said extension 5 on a predetermined angle for a purpose to be hereinafter more particularly referred to. The outer end of the 40 extension 5 or more particularly the meeting portions of the flanges 8 thereof has pivotally engaged therewith a second hook member 20 also adapted to be engaged over the head of a rail and which is also engaged 45 with a rail irrespective of the side of the rail with which my improved device is employed. The hook 21 is engaged with the vertically disposed loop member 22. As is particularly illustrated in Fig. 3, it is also 50 preferred that the inner portion of the hook 20 be also downwardly off-set as indicated at 21 so that no obstruction will be offered to the flange of the wheel riding upon the rail.

When it is desired to replace a car it is to 55 be understood that two of my improved replacers are employed, one coacting with the outer face of one of the rails and the second coacting with the inner face of the second rail of the trackway. After the hook member 60 20 of each of the replacers has been properly engaged with the head of a rail, the lower or entering end of the replacer is properly positioned beneath the tread portion of a wheel of the car. As the car is 65 moved inwardly of the replacers the flange

of one of the wheels will ride in a groove 3 of the replacer coacting with the inner face of the rail and the tread of the second wheel will ride upon the bearing surface as afforded by the intermediate portion 4 and the extension 5. When the wheel riding within a groove 3 is substantially adjacent the upper end thereof, the tread of the wheel will partially overlie the coacting rail so that when the wheel passes from said groove 70 3 it will seat directly on the rail. As the wheel coacting with the bearing surface intermediate the groove 3 passes upwardly thereof, the same will be brought to such an elevation as to position the flange of the 75 wheel above the top of the rail. Upon continued advance of the car this wheel will come in contact with the shoulder 19 which will serve to throw the flange of the wheel over the coacting rail so as to properly seat 80 the wheel on its rail. This movement is afforded by the shoulder 19 and also assures the proper seating of the wheel coacting with the surface 14.

It often occurs that the weight of the car 85 when imposed upon the lower or entering end of the plate P causes said end portion of the plate to sink or lower. By having the hooks 17 and 20 loosely engaged with the vertically disposed loops 16 and 14, respectively, it will be at once self-evident 90 that this movement may be effected without displacing the replacer relative to its rail.

From the foregoing description, it is 95 thought to be obvious that a car replacer 100 constructed in accordance with my invention is particularly well adapted for use by reason of the convenience and facility with which it may be assembled and operated and it will also be obvious that my invention is 105 susceptible of some change and modification without departing from the principles and spirit thereof and for this reason I do not 110 wish to be understood as limiting myself to the precise arrangement and formation of the several parts herein shown in carrying out my invention in practice except as hereinafter claimed.

I claim:

1. A car replacer comprising a body and 115 having its upper surface arranged on a predetermined incline longitudinally thereof, the lowermost portion serving as an entrance, a pair of grooves disposed longitudinally of the body and arranged in the upper 120 face thereof, the portion of the plate intermediate the grooves being flat, said flattened portion affording a bearing surface, said grooves decreasing in depth and width toward their upper ends, the upper end portion of the bearing surface having an up-standing shoulder disposed diagonally thereacross.

2. A car replacer comprising a body and 125 having its upper surface arranged on a pre- 130

determined incline longitudinally thereof, the lowermost portion serving as an entrance, a pair of grooves disposed longitudinally of the body and arranged in the upper 5 face thereof, the portion of the plate intermediate the grooves being flat, said flattened portion affording a bearing surface, and a track engaging member carried by a side of the body, said track engaging member having vertical movement independently of the body.

3. A car replacer comprising a body and having its upper surface arranged on a pre-determined incline longitudinally thereof, 15 the lowermost portion serving as an entrance, a pair of grooves disposed longitudinally of the body and arranged in the upper face thereof, the portion of the plate intermediate the grooves being flat, said flattened portion affording a bearing surface, the bearing surface extending beyond the end of the body remote from the entrance end thereof, the outer end portion of the extension of the 20 bearing surface having an upstanding shoulder disposed diagonally thereacross.

4. A car replacer comprising a body and having its upper surface arranged on a pre-determined incline longitudinally thereof,

the lowermost portion serving as an entrance, a pair of grooves disposed longitudinally of the body and arranged in the upper face thereof, the portion of the plate intermediate the grooves being flat, said flattened portion affording a bearing surface, the bearing surface extending beyond the end of the body remote from the entrance end thereof, the outer end portion of the extension of the intermediate portion converging.

5. A car replacer comprising a body and having its upper surface arranged on a pre-determined incline longitudinally thereof, 40 the lowermost portion serving as an entrance, a pair of grooves disposed longitudinally of the body and arranged in the upper face thereof, the portion of the plate intermediate 45 the grooves being flat, said flattened portion affording a bearing surface, and a track engaging means carried by an end of the body, said track engaging member having vertical movement independently of the body.

In testimony whereof I hereunto affix my signature in the presence of two witnesses.

CHARLES WALTER WATKINS.
